Glynn Campbell and Cecil B. Smith,
Muskogee, Okla.

Application September 15, 1949, Serial No. 5,011

Term of patent 14 years

(Cl. D34—11)

To all whom it may concern:

Be it known, that we, Glynn Campbell and Cecil B. Smith, citizens of the United States, residing at Muskogee, in the county of Muskogee and State of Oklahoma, have invented a new, original, and ornamental Design for a Pig Bank, of which the following is a specification, reference being had to the accompanying drawing, forming part thereof.

In the drawing:

Figure 3 is an end elevation, both ends being alike;

We claim:

The ornamental design for a pig bank, as shown and described.

GLYNN CAMPBELL.
CECIL B. SMITH.
